COMBINED SEAMING AND PINKING MACHINE

Harley C. Moulton, Maplewood, Mo., assignor to
 Lewis Invisible Stitch Machine Company, St.
 Louis, Mo., a corporation of Maine

Application June 26, 1937, Serial No. 150,621

8 Claims. (Cl. 112—122)

This invention relates to new and useful improvements in combined seaming and pinking machines.

In some operations, it is desirable to locate the pinked edge as close to the line of seam as is possible, whereas in other operations this spacing may be increased within limits.

In machines as heretofore constructed, such as is shown in the patents to Popper 1,878,293, 10 September 20, 1932 and 1,886,422, November 8, 1932, and in my prior application filed November 4, 1936, Serial No. 109,175, the stationary ledger blade is provided with a V-shaped opening to receive the vertically reciprocatory V-shaped knife 15 which is maintained in yielding contact with the edges of the ledger blade opening during each cutting stroke. The points of cutting move progressively towards the apex of the ledger blade opening and terminate when the two apices coincide. The knife which is slightly inclined to the vertical, is pivoted at its upper end to an oscillatory power driven knife arm, and spring means are provided for urging the knife towards the apex of the ledger blade opening. The apex of 20 the ledger blade opening is spaced a short distance from the left edge of the blade in order to locate the pinked edge close to the needle. The pinking attachment which is mounted on the base plate of the machine for adjustments 25 towards and from the needle, includes a base to which the ledger blade is attached. This ledger blade projects beyond the end of the attachment base and is located in an opening in the base plate of the machine. Consequently the downward thrust of the knife is resisted by the ledger blade. By reason of the fact that the ledger blade is supported at its right hand end only, 30 said blade will tend to flex downwardly during the cutting stroke of the knife, and occasionally when seams are fed across the blade the pressure of the knife results in the breaking of the blade at the weakest point thereof, viz., the apex.

It will be furthermore observed that in said Popper patents, the throat plate is provided with 35 a bar between the right hand feed dog accommodating opening and the ledger blade for supporting the fabric being pined, and consequently the ledger blade cannot be adjusted closer to the needle than the width of said bar will permit. 40 This is objectionable because in some operations, it is desired to locate the line of pinks closer to the line of seam.

One of the objects of this invention is to provide means for supporting the ledger blade in a manner which will prevent not only the flexing

thereof during the cutting stroke of the knife, but also the occasional breaking of the blade at the apex of the opening thereof.

Another object of the invention is to provide means for oiling the contacting cutting surfaces 5 of the knife and blade and thereby reduce the friction therebetween during the cutting stroke of the knife.

Another object of the invention is to eliminate the right hand bar of the throat plate whereby 10 the left hand edge of the ledger blade may be positioned in its place to thereby support the fabric and also locate the points of the pinks as close as possible to the line of seam.

With these and other objects in view which 15 will more fully appear, the nature of the invention will be more clearly understood by following the description, the appended claims, and the several views illustrated in the accompanying drawings. 20

In the drawings:

Figure 1 is a front elevation of a combined seaming and pinking machine embodying my invention,

Figure 2 is a horizontal section taken on the 25 line 2—2 of Figure 1,

Figure 3 is a detail cross section taken on the line 3—3 of Figure 2, and

Figure 4 is a perspective view showing in separated relation the throat plate and the ledger 30 blade.

Like reference numerals designate corresponding parts throughout the several figures of the drawings.

Referring to the drawings, the sewing machine 35 comprises a frame A which includes a base plate 5, a standard 6, and an overhanging arm 7 which terminates in a needle head 8. A vertically reciprocatory needle 9 is mounted in the head 8 and is operatively connected in the usual manner to 40 the main shaft 10 which is journaled in the overhanging arm 7 whereby the needle will be reciprocated once for each rotation of said shaft. The needle cooperates with a loop taker (not shown) located below the bed plate to form a line 45 of stitches in the usual manner.

The base plate 5, directly below the needle, is provided with an opening 11 which extends longitudinally of the overhanging arm 7 and includes spaced front and rear longitudinally extending walls 12, 13, the upper face of the base 5 along said walls being recessed to form longitudinally extending seats 14, 15 for receiving a throat plate B whereby the upper surface of said throat plate will lie substantially flush with the 50 55

upper surface of the base plate 5, the throat plate being rigidly attached to the bed plate by screws 16, 16.

The throat plate B is substantially U-shaped in construction and includes spaced arms 17, 17 which extend longitudinally of the opening 11, and an integral connecting bar 18 at the left end thereof. A bar 19 is also integral with said arms and is disposed in parallelism with the bar 18 to form a resultant feed dog accommodating slot 20 therebetween. The arms 17, 17 thus project in a general plane at right angles to the slot 20. The bar 19 is provided centrally with an integral offset 21 which projects into the space between the arms 17, 17, and is provided with a needle opening 22. Front and rear flanges 23, 23 which are integral with the inner edges of the arms 17, 17 project inwardly towards each other, and their upper surfaces 24, 24 are disposed below the upper surfaces of the arms 17, 17 to form supporting seats for the ledger blade C, the left ends of the flanges being spaced from the bar 19 to form resultant front and rear feed dog accommodating slots 25, 26 which are respectively located in front and rear of the offset 21 containing the needle opening 22 and in open communication with the space between the arms 17, 17. A vertically yieldable presser foot D is mounted on the head 8 in the usual manner for cooperation with the throat plate B to clamp the fabrics therebetween while the needle is in the fabrics and while the fabrics are being pinked by the vertically reciprocatory V-shaped knife E.

A 4-motion feed dog F which is supported below the base plate 5 for cooperation with the presser foot, includes a feed section 27 which operates in the slot 20 of the throat plate B and aligned front and rear feed sections 28, 29 which operate in the slots 25, 26 of said throat plate.

The ledger blade C is provided with spaced arms 30, 30 which are attached to a pinking attachment base G, and with a V-shaped opening forming converging cutting edges 31, 31 and an apex 32. The cutting edges converge towards the needle, the apex is located centrally between the arms 17, 17 of the throat plate and in alignment with the needle, and the apex is spaced a short distance from the left edge of the blade. The attachment base G is mounted on the bed plate 5 for longitudinal adjustments towards or from the needle by means of a slot 33 formed in said base G and a clamping screw 34 which threadably engages an opening in the base plate 5. Thus, the ledger blade C can be readily shifted towards or from the needle to vary the distance between the line of seam and the line of pinks. The left hand edge of the ledger blade C can be positioned directly against the offset 21 of the throat plate, and consequently the apex 32 of the ledger blade opening will be positioned as close as possible to the needle to thereby permit of the narrowest spacing possible between the line of seam and the line of pinks. It will be observed that the flanges 23, 23 of the throat plate constitute a firm support for the ledger blade in any position of longitudinal adjustment thereof.

The knife E includes converging cutting walls 35, 35 and is pivotally connected as at 36 to the free end of a knife lever 37 which is fulcrumed on the attachment base G as at 38. A yieldable means 39, which is disclosed in my prior application referred to above, is interposed between the knife lever 37 and the knife and functions

to maintain the cutting walls of the knife in yielding contact with the cutting edges of the ledger blade during the cutting stroke of the knife. The angle of the cutting edges of the ledger blade is greater than the angle of the cutting walls of the knife. The knife lever 37 is driven from the main shaft 10 in timed relation to the needle reciprocations through the medium of a driving connection 40 which includes a reduction gear coupling 41.

The blade is provided on opposite sides of the cutting edges 31, 31 with integral and upstanding guide lugs 42, 42 which function not only to maintain the knife in proper registration with the ledger blade opening, but also to prevent the knife escaping said registration should the lower end of the knife during its upstroke be moved above the upper surface of the blade. These lugs are each provided with a downwardly inclined bore 43 extending from the upper outer corner of the lug to the lower inner face thereof, and an oil wick 44 is positioned in said bore for carrying oil or other lubricant to the cutting surfaces of the knife and blade.

The right hand side portion of the foot D overhangs the offset 21 and the left end of the ledger blade and thereby cooperates with the latter to clamp the edges of the fabrics against the blade between the intermittent feed strokes of the feed dog.

It is of course to be understood that the details of structure and arrangement of parts may be variously changed and modified without departing from the spirit and scope of my invention.

I claim:

1. A throat plate for sewing machines, comprising spaced arms and spaced bars connecting said arms and forming a feed dog accommodating slot therebetween, one of said bars having a centrally located integral offset projecting into the space between the arms and provided with a needle opening, said offset forming resultant feed dog accommodating slots located in front of and in rear of said offset and having open communication with the space between the arms of the plate, the arms being provided beyond the offset with depressed flanges extending inwardly towards each other for forming seats for a ledger blade.

2. In a combined seaming and pinking machine, the combination with a vertically reciprocatory needle, a base plate having an opening, a throat plate secured to the base plate and extending across the opening thereof, said throat plate comprising spaced arms and spaced bars connecting said arms and forming a feed dog accommodating slot therebetween, one of said bars having a centrally located integral offset provided with a needle opening and forming resultant feed dog accommodating slots located in front of and in rear of said offset and having open communication with the space between the arms of the throat plate, and a pinking attachment mounted on the base plate on the side of the base plate opening opposite the needle, said attachment including a ledger blade and a co-operating cutting element, the ledger blade being positioned in the base plate opening between the arms of the throat plate and against the offset thereof.

3. In a combined seaming and pinking machine, the combination with a vertically reciprocatory needle, a base plate having an opening, a throat plate secured to the base plate and extending across the opening thereof, said throat

plate including spaced bars forming a feed dog accommodating slot, one of the bars having a centrally located offset projecting into the base plate opening and provided with a needle opening and forming resultant feed dog accommodating slots located in front of and in rear of said offset and having open communication with said base plate opening, a presser foot cooperating with the throat plate and having a side portion overhanging the offset and the base plate opening, and a pinking attachment mounted on the base plate on the side of the base plate opening opposite the needle, said attachment including a ledger blade and a cooperating cutting element, the ledger blade being positioned in the base plate opening and having one end positioned under the overhanging side portion of the presser foot and against said offset.

4. In a combined seaming and pinking machine, the combination with a vertically reciprocating needle, a base plate having an opening, a throat plate secured to the base plate and extending across the opening thereof, said throat plate including spaced bars forming a feed dog accommodating slot, one of the bars having a centrally located offset projecting into the base plate opening and provided with a needle opening and forming resultant feed dog accommodating slots located in front of and in rear of said offset and having open communication with said base plate opening, a presser foot cooperating with the throat plate and having a side portion overhanging the offset and the base plate opening, a pinking attachment mounted on the base plate on the side of the base plate opening opposite the needle, said attachment including a ledger blade and a cooperating cutting element, the ledger blade being positioned in the base plate opening and having one end positioned under the overhanging side portion of the presser foot and against said offset, and means secured to the throat plate for supporting said ledger blade against the thrust of the knife.

5. A combined seaming and pinking machine including a reciprocable needle, and a pinking mechanism disposed at one side of the needle

and including a horizontally disposed ledger blade having an opening forming converging cutting edges, and a knife movable upwardly and downwardly with respect to the ledger blade and having converging cutting walls, guide lugs projecting from the ledger blade at opposite sides of the opening therein for maintaining the cooperative relation of said knife and blade, and means supported by said lugs for directing a lubricant to the cutting walls of the knife.

6. A combined seaming and pinking machine including a reciprocable needle, and a pinking mechanism disposed at one side of the needle and including a horizontally disposed ledger blade having an opening forming converging cutting edges, and a knife movable upwardly and downwardly with respect to the ledger blade and having converging cutting walls, guide lugs projecting from the ledger blade at opposite sides of the opening therein for maintaining the cooperative relation of said knife and blade, and means supported by said lugs for directing a lubricant to the cutting walls of the knife, said means comprising a bore formed in each lug and communicating with the inner face thereof, and a lubricant-carrying wick in said bore.

7. In a combined seaming and pinking machine, a base plate having an opening, a throat plate supported by the base plate and extending across said opening and provided with a needle opening and a feed dog accommodating slotway, and a horizontal ledger blade supported by said throat plate and partially defining said slotway.

8. In a combined seaming and pinking machine, a base plate having an opening, a throat plate supported by the base plate and extending across said opening and provided with a needle opening and a feed dog accommodating slotway, said throat plate being provided with spaced laterally extending arms disposed along the front and rear edges of the base plate opening, a ledger blade supported on said arms, and means positioning said ledger blade on said arms so that a portion thereof partially defines said slotway.
